UNITED STATES PATENT OFFICE.

EDWIN E. BEAN, OF BOSTON, MASSACHUSETTS, ASSIGNOR TO THE CONSOLIDATED WAX-THREAD SEWING-MACHINE COMPANY, OF SAME PLACE.

IMPROVEMENT IN WAX-THREAD SEWING-MACHINES.

Specification forming part of Letters Patent No. 159,144, dated January 26, 1875; application filed August 3, 1874.

To all whom it may concern:

Be it known that I, EDWIN E. BEAN, of Boston, in the county of Suffolk and State of Massachusetts, have invented certain new and useful improvements in Wax-Thread Sewing-Machines; and I do hereby declare that the following is a full, clear, and exact description thereof, which will enable others skilled in the art to which it pertains to make and use the same, reference being had to the accompanying drawings and to the letters of reference marked thereon, which form a part of this specification.

My invention relates to improvements in wax-thread sewing-machines, consisting in the employment of a crank on the driving-shaft and a link-connection, in combination with an intermediate connecting mechanism to the needle-bar, by means of which the latter is moved in a vertical direction, as will now be more fully shown and described.

On the drawing, Figure 1 represents a side elevation of a wax-thread sewing-machine embodying my invention; and Fig. 2 represents a cross-section on the line A B, shown in Fig. 1.

Similar letters refer to similar parts wherever they occur on the drawings.

a represents the rotary driving-shaft. b is the rock-shaft in the goose-neck of the machine, for the operation of the awl and presser-foot; and c represents the rock-shaft below the work-plate d, for the operation of the needle and cast-off in a vertical direction in the ordinary way. e represents a grooved disk, secured to the shaft a as usual. To the face of the disk e is secured a pin or stud, f, by which, and a suitable connecting mechanism, the respective movements are imparted to the awl and presser-foot above the work-plate, and to the needle and cast-off below the said work-plate.

I claim nothing new in the connecting mechanism for the operation of the awl and presser-foot in a vertical direction, as the connecting mechanism from the crank-pin f to the awl and presser-foot, as shown in the accompanying drawing, is old and well known; but my invention relates to a new and useful connecting mechanism from the crank-pin on the driving-shaft to the needle-bar, for the purpose of operating the needle and cast-off in a vertical direction.

Formerly the crank-pin f did work in a

curved slot on a rocking arm, from which a rocking motion was conveyed to the shaft below that operates the needle-bar. Such a curved slot is expensive to make, creates a great friction during its operation, and is hard to keep properly lubricated; therefore, to avoid this difficulty, I employ a link-connection, g, hinged in its upper end to the crank-pin f, and in its lower end to a rocking lever, h, that is movable on the fulcrum i, as shown. The lever h is provided with a slotted arm or extension, k, having a slot, k', in which the set-screw l is made adjustable. To the set-screw l is jointed a link, m, the lower end of which is hinged to the upper end of a rocking lever, n, that is keyed or otherwise secured to the shaft c in the usual manner. The needle-bar and cast-off bar are operated from the shaft c by means of a lever and link-connection, as usual. The throw of the needle in a vertical direction can be adjusted by changing the position of the set-screw l in the slot k'.

By the employment of a single crank and a link-connection with the intermediate connecting mechanism to the needle and cast-off bars, as herein shown, a very positive motion is at all times obtained for the operation of said bars in a vertical direction. Another advantage is obtained in the employment of a link-connection as compared with the grooved cams, slotted levers, and other devices heretofore used for this purpose, in that this kind of link-connection is not liable to become disarranged by use, and after being once properly adjusted it does not need a skilled operator to run the machine. It also requires less repairs than other connecting devices heretofore used for this purpose.

Having thus fully described the nature, construction, and operation, of my invention, I wish to secure by Letters Patent and claim—

In combination with the driving-shaft a and the crank-pin f, the link-connection g and the intermediate connecting mechanism to the rock-shaft c, substantially as herein shown and described.

In testimony that I claim the foregoing as my own invention I have affixed my signature in presence of two witnesses.

EDWIN E. BEAN.
